UNITED STATES PATENT OFFICE.

FRANK X. LIST, OF NEW YORK, N. Y., ASSIGNEE TO NATIONAL CARD MOUNTING COMPANY, OF NEW YORK, N. Y., A CORPORATION OF NEW YORK.

DISPLAY BOX.

1,408,814.

Specification of Letters Patent. Patented May 7, 1922.

Application filed March 14, 1919. Serial No. 233,522.

To all whom it may concern:

Be it known that I, FRANK X. List, a citizen of the United States, and a resident of the city of New York, county of Bronx, and State of New York, have invented certain new and useful Improvements in Display Boxes, of which the following is a specification.

This invention relates to display boxes and has for its primary object to provide an improved box of this character constructed of cardboard and provided with means whereby the box may be supported at an inclination relative to a horizontal plane, in order to display the contents thereof. It is another object of my invention to provide simple and effective means for retaining the lid or cover of the box in open position.

The invention also contemplates the provision of a display box constructed from a one-piece cardboard blank and having the above noted desirable features, the supporting means for the body of the box and the lid or cover being capable of compact arrangement so that they will not protrude from the box walls when the box is closed and wrapped; and it is a further general object of the invention to provide a cardboard display box wherein the several parts of the blank may be easily and quickly folded and adjusted into their proper relative positions.

With the above and other objects in view the invention consists in the improved construction, combination and arrangement of the several parts to be hereinafter more fully described and subsequently incorporated in the subjoined claims.

Referring to the accompanying drawings wherein like reference characters designate corresponding parts throughout the several views:

Fig. 1 is a plan view of the blank from which the improved box is formed;

Fig. 2 is a perspective view showing the box partially set up or folded;

Fig. 3 is a transverse sectional view through the box;

Fig. 4 is a horizontal section taken on the line 4-4 of Figure 3; and

Fig. 5 is a detail vertical section through one end of the box taken on the line 5-5 of Figure 3.

In the construction of the improved display boxes I preferably employ heavy card-

board or paper. The blank from which each box is formed includes the main bottom wall 5, the front longitudinal or side wall 6, rear longitudinal wall 7 and end walls 8. The cardboard is scored at the juncture of 60 the side and end walls with the bottom wall 5 as indicated at 9 so that such side and end walls may be readily bent or folded to erect position with respect to the bottom wall.

The blank also includes an inner front 65 side wall 10 which is in fact a continuation of the wall 6 and is adapted to be bent over and along the score line 11 upon the inner face of the wall 6. 12 designates a false bottom wall for the box extending from the 70 inner side wall 10 and bendable along the score line 13 to lie in a plane at right angles to the wall 10 and in superposed relation to the main bottom wall 5 when the box is folded in the manner to be hereinafter described.

The outer end walls 8 of the box are provided with foldable extensions to form inner end walls 14, said latter wall being bendable with respect to the wall 8 along the 75 score line 15. These supplementary or additional end walls 14 are each provided at one end with a flap or extension 16 which is adapted to be bent at its juncture with the wall 14 along the score line 17.

The outer front wall 6 of the box structure is likewise provided at its ends with the flaps or extensions 18 and the rear side wall 7 is also provided with the relatively long flaps 19. These flaps 18 and 19 are 80 bendable along the lines 20 and 21 respectively to extend at right angles to the side walls of the box.

The box lid or cover 22 which is practically a continuation of the rear wall 7 is 85 bendable along the score line 23 and this lid at its opposite ends and contiguous to the flaps 19 is formed with the lateral extensions 24. Each of these extensions is adapted to be bent along the obliquely extending score line 25 and the end of the extension is preferably curved or rounded as shown at 26 for the purpose which will be later disclosed.

The lid 22 is further provided on its free 90 longitudinal edge and centrally thereof with the tongue 29.

The box blank at the juncture of the two front side walls 10 and 11 is slit or cut as shown at 30 to receive the tongue 29 of the 95

box lid. The main bottom wall 5 of the box is also cut to provide a substantially rectangular section 31 which however remains integrally connected along the score line 32 with the bottom wall of the box. At the relatively opposite edge of the section 31 and centrally thereof a tongue 33 is formed. This cut-out section intermediate of its opposite longitudinal edges is scored or weakened as at 34. The box blank is also provided with a slit 35 at the juncture of the bottom wall 5 with the rear wall 7 thereof to receive the tongue 33.

Having thus described the several structural features of my improved box, the manner in which the blank is to be folded and the several parts thereof relatively arranged may be explained as follows:

The blank is bent along the longitudinal score lines 9 to dispose the front and rear side walls 6 and 7 in their erect positions. The flaps or extensions 18 and 19 are then bent inwardly and at right angles to the side walls, the flap 18 being lapped upon the inner side of the flap 19. The end wall 8 is now bent upwardly and engaged against the out sides of the flaps 18 and 19. After bending the flap 16 in an outward direction from the end of the wall 14, this wall is bent inwardly along the score line 15 and downwardly against the inner faces of the flaps 18 and 19, the flap 16 then extending longitudinally along the inner face of the front wall 6. It will of course be understood that each end of the box blank is folded in the manner just described. The longitudinal wall 10 is now bent inwardly and downwardly along the line 11 to overlie the flaps 16. In this folding operation the false bottom wall 12 is at the same time bent along the score line 13 so as to extend over and upon the main bottom wall 5.

After thus arranging the several parts of the box body in their erect and folded positions, the lid or cover 22 is bent outwardly along the score line 23. The extensions 24 at the opposite ends of the lid are then folded along the oblique score lines 25 so that the two parts of the extension 24 are in close contact. The longer part of the extension 24 having the rounded end 26 is then inserted between the outer end wall 8 and the flap 19 which extends inwardly from the rear wall 7. The frictional contact of the folded extensions 24 with the end walls and the flaps 19 serves to retain the box lid or top in its open position and likewise prevents the further opening downward movement of the lid.

In the use of the box for display purposes, in order to display the contents thereof in a store window or case to the best advantage, it is desirable that the box body be tilted and supported at an inclination to a horizontal plane. I accomplish this pur-

pose by pulling the section 31 outwardly from the plane of the box bottom and then bending said section along the score line 34 to provide two portions extending in diverging relation to each other. The tongue 33 on the free longitudinal edge of the section 31 is inserted upwardly through the slit 35 at the juncture of the bottom wall 5 with the rear wall 7 of the box. Thus it will be seen that the folded extension 31 in conjunction with the box bottom constitutes a longitudinally extending prop or support of triangular form in cross section, the apex of such prop resting upon the floor, stand or other base.

From the foregoing description taken in connection with the accompanying drawings, the construction and several advantages of the improved display box will be clearly and fully understood. After becoming familiar with the box construction, the blank may be very easily and quickly folded. Such construction provides a box which will be very rigid and substantial and by folding the several parts in the manner above explained, the box structure is not liable to easily collapse. By providing the prop or support as an integral part of the box structure, a relatively large number of display boxes may be arranged in a case or window without additional support therefor and the contents of the box displayed to the very best advantage. When the box and its contents are sold, the tongue 33 on the section 31, which forms the prop, is removed from the slit 35 and such section is returned to its original position within the plane of the bottom wall 5. The supporting flaps or extensions 24 for the box lid are then removed from between the end walls 8 and the flaps 19 and are folded inwardly against the lid or cover 22. The lid is then folded down over the contents of the box and the tongue 33 is bent at right angles to the lid and inserted through the slit 30 at the juncture of the inner and outer front walls 10 and 6. Thus it will be seen that when the box is closed, there are no protruding parts so that the box may be tightly and neatly wrapped. Owing to the fact that the display box is constructed from a single card, board or paper blank which may be readily stamped or cut out, it will be appreciated that the invention can be produced at comparatively small manufacturing cost. It will of course be understood that the box may be produced in various sizes and of other dimensions than those indicated in the accompanying drawings, as may be necessitated in view of the particular purpose or use for which the box is designed.

Accordingly, while I have herein shown and described one practical embodiment of the invention, it is to be understood that the device may also be exemplified in various

other alternative constructions without departing from the spirit or scope of the invention as claimed.

I claim:

5. 1. A display box constructed of cardboard and having a section cut from its bottom wall and integrally connected thereto, said section being foldable backwardly upon itself and upon the bottom to constitute a prop for the box and support the same at an inclination relative to a horizontal plane.

10. 2. A display box constructed of cardboard and having a section cut from its bottom wall and integrally connected thereto, said section being foldable and having a part co-acting with the box body and retained relatively thereagainst by the pressure of the section to retain said section in its folded position, whereby the folded section constitutes a prop for the box to support the same at an inclination relative to a horizontal plane.

15. 3. A display box constructed of bendable material and having a section cut from its bottom wall and integrally connected thereto, the bottom wall having a slit therein, said section adapted to be displaced from the plane of the bottom wall and foldable backwardly upon itself and upon said bottom wall and having a part insertable through said slit to retain the extension in position to constitute a prop for the box and support the same at an inclination relative to a horizontal plane.

20. 4. A display box constructed of bendable material and having main and false bottom walls, the main bottom wall having an adjustable section cut therefrom and integrally connected thereto and adapted to be rolled upon itself and co-act with the bottom wall to constitute a prop for the box and support the same at an inclination relative to a horizontal plane.

25. 5. A display box constructed of cardboard and having main and false bottom walls, the main bottom wall of the box being provided with a slit at one longitudinal edge thereof, and a section integral with said wall and adapted to be extended from the plane thereof and folded backwardly upon itself to provide diverging parts, one of said parts having a tongue insertable through said slit to retain the extension in its folded position, whereby such extension constitutes a prop for the box to support the same at an inclination relative to a horizontal plane.

30. 6. A display box constructed of cardboard and having foldable side and end walls and a lid extending from the rear side wall and bendable with respect thereto,

said rear side wall having flaps extending longitudinally along the inner sides of the end walls, and a lateral extension integral 65 with the box lid, said extension being foldable upon itself to provide a part for insertion between one of the end walls and the associated flap of the rear wall.

7. A display box constructed of cardboard, having side and end walls and a lid integral with the rear side wall and bendable to an open angular position with respect thereto, an integral lateral extension on each end of the lid foldable upon itself 75 to provide a part to co-act with the adjacent end wall of the box to sustain the lid in its open position.

8. A one-piece display box blank cut to provide a bottom and integral side and end 80 walls with an integral cover on the rear side wall, said blank having formed in the bottom portion thereof an integral prop adapted to be folded into position for supporting the folded blank at an inclination 85 to the horizontal, and said blank having integrally formed thereon means for supporting said cover at a rearward inclination on the folded blank to disclose the interior of the formed box. 90

9. A display box constructed of cardboard and having integral means displaced from the box body and forming a prop whereby the box may be supported at an inclination to the horizontal to better display the contents of the box, a lid for the box integral with the box body and hingedly joined therewith, and foldable means integral with the lid adapted to be turned over upon itself to project forwardly at its free 100 end and adapted to engage with the end walls of the box whereby the lid may be held in a rearwardly inclined position with respect to the rear elevated side wall of the box whereby not to obstruct inspection of 105 the contents of the box.

10. A one-piece display box blank cut to provide a bottom and integral side and end walls with an integral cover on the rear side wall, said blank having formed in 110 the bottom portion thereof an integral prop adapted to be folded into position for supporting the folded blank at an inclination to the horizontal, and said blank having integral therewith foldable sections adapted 115 to be turned over upon themselves to project forwardly and interlock with the side walls of the box for supporting said cover at a rearward inclination on the folded blank to disclose the interior of the formed box. 120

In testimony that I claim the foregoing as my invention, I have signed my name hereunder,

FRANK X. LIST.
